LAPEL PIN

Oscar A. Eriksen, San Francisco, Calif., assignor
to Van Wormer & Rodrigues, Inc., San Fran-
cisco, Calif., a corporation of California

Application October 6, 1952, Serial No. 21,735

Term of patent 7 years

(Cl. D45—19)

To all whom it may concern:

Be it known that I, Oscar A. Eriksen, a citizen of the United States, residing at San Francisco, State of California, have invented a new, original, an ornamental Design for a Lapel Pin, of which the following is a specification, reference being had to the accompanying drawing, forming a part thereof.

Fig. 1 is a front elevational view of a lapel pin showing my new design;

Fig. 2 is a rear elevational view thereof;

Fig. 3 is a side elevational view thereof taken from the left of Fig. 1;

Fig. 4 is a side elevational view thereof taken from the right of Fig. 1;

Fig. 5 is a bottom plan view thereof; and

Fig. 6 is a top plan view thereof.

I claim:

The ornamental design for a lapel pin, substantially as shown.
